(57) **CLAIM**

The ornamental design for a cord protector, as shown and described.

DESCRIPTION

FIG. 1 is a perspective view of a cord protector in a closed position and in accordance with our new design;

FIG. 2 is a top view thereof.

FIG. 3 is a bottom view thereof.

FIG. 4 is a front view thereof.

FIG. 5 is a rear view thereof.

FIG. 6 is a left side view thereof.

FIG. 7 is a right side view thereof; and,

FIG. 8 is a perspective view of the cord protector in an open position.

The broken lines shown represent portions of the cord protector that form no part of the claimed design.
